Primary Examiner — Michael A. Pratt*(74) Attorney, Agent, or Firm* — Womble Carlyle Sandridge & Rice LLP**(57) CLAIM**

The ornamental design for a firearm bullet, as shown and described.

DESCRIPTION

FIG. 1 is a top perspective view of a bullet, wherein a pair of substantially horizontal, closely adjacent broken lines is included for indicating that no particular length is being claimed;

FIG. 2 is a bottom perspective view of the bullet of FIG. 1; FIG. 3 is a front elevation view of the bullet of FIG. 1; FIG. 4 is a top plan view of the bullet of FIG. 1; FIG. 5 is a bottom plan view of the bullet of FIG. 1; and, FIGS. 6-10 are respectively like FIGS. 1-5 except that shading is not shown, and diagonal hatching designates the color green and horizontal hatching designates a color that is different from the color designated by the diagonal hatching.

1 Claim, 4 Drawing Sheets(56)
